SEALING ELEMENT FOR FLUID-PRESSURE CONTAINERS

Herman Koester, Waterbury, Conn., assignor to
The Bristol Company, Waterbury, Conn., a corporation of Connecticut

Application November 29, 1933, Serial No. 700,333

8 Claims. (Cl. 297—3)

The invention relates to means for sealing a container for fluids under pressure, for example, metal thermometer bulbs adapted to contain a volatile or expansible fluid and to which vessel is to be connected a capillary tube placing the bulb in communication with a suitable measuring instrument.

In the use of these bulbs, it has been found expedient to form the same of a section of drawn tubing, having its one end closed and its other normally open but adapted to be closed by a suitable plug or bushing of metal which is soldered or brazed into place. This plug, also, provides the connection for the capillary tube which is arranged to pass through a longitudinal opening or duct of the plug, and is, in turn, sealed to the latter into its final position.

In forming these plugs from metal, it has been customary to employ either a casting or rolled or drawn bar stock, the plug being formed to shape in a lathe and subsequently assembled to the fluid-pressure containing vessel as hereinbefore set forth. These is a tendency, however, for leaks to develop through the apparently solid metal of the plug when the same is assembled as noted. This I have found to be due, in the case of rolled or drawn stock, to "pipes" or striae in the mass of the metal, whose general direction is determined by the asymmetric treatment. These inclusions, notwithstanding the rolling or drawing operations, prevent a complete seal by the plug; and under the high pressures involved, permit a seepage of the volatile contents of the vessel through the exceedingly small interstices. In the case of cast plugs, the natural porosity of the casting, and possible blow-holes in the metal, may result in similar leakage, so that a leak-proof construction cannot thereby be assured.

The present invention has for an object the provision of a plug or sealing element wherein this objectionable feature is eliminated.

In carrying out the invention, provision is made for a cap designed to fit over the inner end of the usual plug member to be suitably secured thereto at the rim of the cap, as well as to the bulb or like vessel, said cap being of a material impervious to the fluid under pressure within the vessel, as of wrought metal such as metal pressed or rolled from sheet stock or forged. When the cap is thus placed over the plug end, any striated inclusions of the cap will then be disposed in a direction normal to the direction of the pressure exerted upon the bottom of the cap. This effectively prevents passage of the fluid through the said bottom of the cap and thus insures a leak-proof

construction of the plug for sealing the outlet of the bulb.

The nature of the invention, however, will best be understood when described in connection with the accompanying drawing, in which:

Fig. 1 is an exploded view, in perspective, illustrating the invention as embodied in a thermometer bulb.

Fig. 2 is a fragmentary longitudinal section through the outlet end of a bulb and a sealing plug fitted therein in accordance with the invention.

Referring to the drawing, 10 designates a vessel, as of metal, and, for example, such as a thermometer bulb adapted to contain a volatile or expansible fluid. The said vessel may be formed of drawn tubing having the one end 11 permanently closed and open at its opposite end to provide the outlet 12.

This outlet is designed to be closed by a suitable plug or sealing element comprising the body portion 13 having the longitudinal axial duct 14 extending therethrough. The plug may also be provided with a flanged section 15 and a threaded outer end 16 to provide attachment between the plug and suitable fittings or fixtures (not shown) for connection of the bulb in position for use. A capillary tube 20, Fig. 2, is designed to pass through the duct 14 in the usual manner to connect the interior of the bulb 10 with a suitable measuring instrument or the like (not shown), it being understood that the inner end of the plug fits within the outlet 12 and that the capillary tube will project into the space of the said bulb, all of which is well understood and forms no particular part of the present invention.

The present invention is concerned more especially with the provision of means for securing a leak-proof seal between the said plug and the said capillary tube and bulb at the outlet of the latter. In accordance with the invention, the inner end of said plug is not directly fitted to the outlet end of the bulb as has been the practice heretofore, but a cap element 21 is arranged to be fitted over said end of the plug, as more clearly set forth in Fig. 2 of the drawing. This cap is in the form of a cup composed of a material impervious to the fluid under pressure, for example, pressed or drawn sheet metal, the side walls extending over the body member 13 when the sealing member is assembled. The bottom of the cap is also perforated as at 22, in the present instance axially to register with

the duct 14 through the plug so as to pass the capillary tube 20 to the interior of bulb 10.

It is preferred, also, to upset inwardly the material of the bottom of the cap in the piercing of the same so that the upset portion 23 will afford excess metal to give the opening 22 a somewhat greater axial length than the thickness of the bottom of the cap. This will simplify sealing of the capillary tube 20 to the bottom 10 of the cap, as by soldering or brazing the same thereto. At its rim 24, the cup is to be soldered or brazed not only to the body portion 13 of the plug, but as well to the outer end of the bulb 10, the rim to this end being disposed, preferably, so as to lie slightly within the edge of the bulb 10, as indicated in Fig. 2. The seal effected thus at the three adjacent surfaces of plug, cap and bulb, is secure and tight at this point, it being understood that the thickness of the cap 20 wall is such as to substantially fill the annular space between the external surface of the plug covered by the cap and the juxtaposed inner surface of the bulb.

Furthermore, it will be noted that when the cap 21 is thus interposed between the plug and the bulb, though the said plug may have striae within its mass, as indicated at 25, the cap 12 separating the inserted end of this plug from the interior of the bulb 10, will prevent communication of the fluid pressure from within said interior space to these striae. Moreover, since any such striae, as indicated at 26, which might be present in the cap 21 would be the arrangement hereinbefore described be located parallel 30 to the plane of the bottom of the cap, they would therefore be disposed in a direction normal to the pressure applied to said bottom, and thus serve to render the cap bottom and thereby the plug itself impervious to the passage of fluid contained 35 within the bulb 10.

By thus providing for the application of the pressure transversely to any striae of the metal cap and by sealing the joints in the manner described, the closure as a whole is substantially 40 impervious to the fluid under the pressures developed within the bulb.

It is to be noted, also, that where the plug is intended for use merely to close or seal off the end of a vessel, the perforation provided in 50 the cap will of course not be necessary and may be omitted, and no outlet tube will pass through the plug so that the duct thereof may also be omitted.

I claim:

55 1. A sealing element for fluids under pressure, said element comprising a tubular metal body member and a wrought metal cap enclosing an end thereof to be exposed to the pressure, with the grain of the cap in a direction substantially 60 normal to said pressure.

2. The combination with a vessel adapted to retain a fluid under pressure, of an element comprising a hollow metal body adapted for insertion into an outlet of the vessel, and a wrought metal cap fitted over an end of the body member exposed to said pressures, said cap being sealed thereto and to the vessel.

65 3. The combination with a vessel adapted to

retain a fluid under pressure, of an element comprising a tubular body member adapted for insertion into an outlet of the vessel, and a metal cap fitted over the inserted end of the body member, sealed to the inserted end of the body member and to the vessel and impervious to the fluid under pressure in the direction of pressure exerted upon the cap bottom.

4. The combination with two tubular metal members of a sealing element for joining the same in fluid-pressure-sealed relationship—the one of said members being of a diameter to fit within the other and having an end inserted therein, a metal cap secured over the inserted end, sealed at its rim to both of the said members and 10 impervious to the fluid under pressure in the direction of the pressure exerted upon the cap bottom.

5. The combination with two tubular metal members, of a sealing element for joining the same in fluid-pressure-sealed relationship—the one of said members being of a diameter to fit within the other and having an end inserted therein, and a cupped wrought metal cap whose side walls extend over the inserted end of the one 20 tubular member and the bottom of the cap being exposed to pressure within the other and its rim being sealed to both members.

6. The combination with two tubular metal members, of a sealing element for joining the same in fluid-pressure-sealed relationship—the one of said members being of a diameter to fit within the other and having an end inserted therein, and a cupped wrought metal cap whose side walls extend over the inserted end of the one 30 tubular member and the bottom of the cap being perforated with upset material therefrom 35 extending inwardly of the cap for sealing thereof tubing adapted to pass through the inserted member into the other member, said cap being exposed to pressure within the latter member and its rim being sealed to both members.

7. In combination: a tubular vessel having an outlet and adapted to retain a fluid under pressure, a tubular member extending into the said outlet, tubing extending through the tubular member into the said vessel, and a wrought metal cap fitted over the inner end of the tubular member and about the tubing, the bottom of the cap being perforated to pass the tubular member and the rim of said cap being sealed to the body portion and to the vessel and the tubing at the perforation to the cap.

8. A plug for joining a capillary tube to a bulb adapted to retain a fluid under pressure, said plug comprising a metal body member adapted for external connection and having a longitudinal duct through which an end of the capillary tube is adapted to pass, and a cap fitting over the said end of the body member, of wrought metal and having a bottom perforation for registry with the duct of the body member when the said cap is fitted over the end thereof, said cap being sealed at its rim to the body member and at its perforation to the capillary tube, and the plug as a whole being adapted to be sealed to the bulb at the rim of said cap.

HERMAN KOESTER.
